PARACHUTE

Harry G. Shaffer, Pierce City, Mo., assignor of
three thirty-seconds to Henry Badger, Lawrence
County, Mo.

Application October 25, 1938, Serial No. 236,941

8 Claims. (Cl. 244—149)

My invention relates to parachutes, and has among its objects and advantages the provision of improved means for positively opening the parachute and a novel control for maneuvering the parachute.

An object of my invention is to provide a novel means for controlling the descent of the parachute to the end that dangers or unsuitable landing spaces may be avoided through means under the control of the jumper. The parachute is characterized by a valve which may be actuated for hastening a dangerous lateral drift or to retard the descent so as to be carried by the wind to a lateral position beyond, for example, a preselected objective.

Another object is to provide a parachute designed to be folded in a compact manner, in which novel means are incorporated for positively opening the parachute without the aid or attention of the jumper other than his weight in combination with the effective air resistance on the parachute.

In the accompanying drawing:

Figure 1 is an elevational view of a parachute embodying my invention;

Figure 2 is an enlarged sectional view along the line 2—2 of Figure 1;

Figure 3 is a sectional view along the line 3—3 of Figure 4;

Figure 4 is a top plan view of the structure illustrated in Figure 3;

Figure 5 is a perspective view of a portion of a parachute opening means; and

Figure 6 is a fragmentary view of the opening means illustrating the manner in which the structure may be folded.

In the embodiment selected to illustrate my invention, the parachute comprises a bulb-shaped canopy 10 narrowing downwardly into a neck 12 having an open end 14 for the admission of air. Neck 14 is of sufficient diameter to lend the necessary carrying capacity to the parachute. Canopy 10 may comprise canvas and is reinforced by cords 16 which extend vertically of the canopy and about its top curvature. The usual ring 18 is carried by the canopy 10 through the medium of shroud lines 20, and the ring 18 is provided with the usual seat 22.

At the apex of the canopy 10 I provide a valve 24 which may be opened and closed at the will of the jumper for releasing or trapping air inside the sail. Referring to Figure 3, the canopy 10 is provided with an opening 26 reinforced by a metallic ring 28. A ring 30 is positioned on the opposite side of the canopy 10 and is fixedly

related thereto as well as to the ring 28 by rivets 32. Thus the margin of the canopy 10 about the opening 26 will be effectively reinforced.

Ring 30 is provided with a flange 34 constituting a seat for a valve element 36 having a peripheral flange 38 arranged to be brought into seating relation with the flange 34. Centrally of the valve element 36 I anchor a tube 40, which tube extends loosely through an opening in a metallic strap 42 having right-angular runs 44 terminating in right-angular lips 46 fixedly anchored to the ring 30 by the rivets 32.

The upper end of the tube is provided with a pin 48 which constitutes an abutment for a washer 50 against which I position one end of a compression spring 52. Spring 52 embraces the tube 40 and has its opposite ends arranged in abutting relation with the strap 42. Thus the tension of the spring 52 normally urges the valve 36 to the closed position of Figure 3.

To the pin 48 I connect one end of a pull rope 54 which extends downwardly inside the tube 40 and downwardly through the canopy within reach of the jumper occupying the seat 22. Valve element 36 lies underneath the seat flange 34 so as to be urged thereagainst by the spring 52 as well as the air under pressure in the canopy. However, the valve element 36 may be opened by exerting a pull on the rope 54. Thus the valve 36 may be actuated for venting the canopy to control the descent of the parachute. In this way, the parachute may be maneuvered so as to shorten a dangerous lateral drift.

I provide a means for positively opening the sail 10. The opening means are indicated at 56 and 58 in Figure 2. Both units 56 and 58 are identical in construction and operation so that the description of one or a portion thereof will apply to the other. Neck 12 is folded back upon itself at 60 and the fold is made secure by stitching 62 or other suitable means. Units 56 and 58 are semi-circular in general configuration, as in viewing Figure 2. Referring to Figures 2, 5 and 6, the unit 56 is made up of bars 64 alternately positioned between double bars 66. The ends 45 of the bars 64 are pivotally connected at 68 with the ends of adjoining double bars 66.

Joints 68 comprise sleeves 70 passed through aligned openings in the overlapping bars 64 and 66 and the sleeves 70 are upset at 74. Alternate joints 68 are attached to the neck 12 at the hem area, as indicated at 76 in Figure 2. The hem area of the neck 12 may be provided with eyelets, one of which is illustrated at 78 in Figure 5, for the reception of sleeves 70 corresponding to those 55

openings. Thus alternate joints 68 are connected with the neck 12 while the remaining alternate joints are unattached. However, the joints attached to the neck 12 retain their pivotal action.

5. The hem area is provided with a plurality of eyelets 80 through which the shroud lines 20 are passed and extended through alternate sleeves 70 and knotted, as at 82.

Bars 64 each has one end extended at 84 beyond its respective pivotal point 68 and is provided with a right-angular lip 86 arranged to engage underneath the adjoining bars 66 to restrain further pivotal movement after the bars have been aligned according to Figure 5. In the absence of a pull on the shroud lines 20, the pivotally connected bars 64 and 66 may be collapsed according to Figure 6 so as to permit folding of the neck 12. Shroud lines 20 slide freely through the eyelets 80 and, when a pull is exerted on the shroud lines, pull downwardly on their associated joints 68 for moving the bars into a straight line. Figure 6 illustrates the jointed bars partly folded at which time a pull on the shroud lines 20 will straighten the folded bars for opening the neck 12 to the circular configuration of Figure 2. Units 56 and 58 are spaced slightly at their ends, as at 88, in Figure 2, so that the two linkage units may be folded into compact relation.

30. Without further elaboration, the foregoing will so fully illustrate my invention that others may, by applying current knowledge, readily adapt the same for use under various conditions of service.

I claim:

35. 1. A parachute comprising a canopy having an open neck, eyelets carried by said neck, seat supporting shroud lines threaded loosely through said eyelets, a normally collapsed linkage encircling said neck and connected therewith with the elements of the linkage so connected and arranged as to provide a rigid ring for positively opening and holding the neck in a full open position, and operating connections between the shroud lines and said linkage for moving the latter to its neck opening position when a pull is exerted on the shroud lines.

40. 2. A parachute comprising a canopy having an open neck, eyelets carried by said neck, seat supporting shroud lines threaded loosely through said eyelets, and a foldable linkage encircling the neck and connected with the latter for positively opening and holding the neck in a full open position, said foldable linkage comprising a plurality of pivotally connected bars having alternate pivotal connections connected to said neck and the other pivotal connections connected with said shroud lines in such manner as to move the linkage to its neck opening position when a pull is exerted on the shroud lines.

45. 3. A parachute comprising a canopy having an open neck, eyelets attached to said neck, a foldable linkage operatively connected with said neck for positively opening and holding the same in a full open position, and shroud lines threaded through said eyelets and operatively connected with said linkage for moving the latter to its neck opening position when a pull is exerted on the shroud lines.

50. 4. A parachute comprising a canopy having an open neck, eyelets carried by said neck, seat

supporting shroud lines threaded loosely through said eyelets, means for positively opening and holding the neck in its full open position, said means comprising a plurality of bars having pivotal connections at their ends one with the other, alternate pivotal connections comprising eyelets, the other of said pivotal connections being connected with the neck, and operating connections between the shroud lines and said certain of said pivotal connections so constructed and arranged as to move the bars to their neck opening position when a pull is exerted on the shroud lines. 5

5. A parachute comprising a canopy having an open neck, eyelets carried by said open neck, means for positively opening and holding the neck in a full open position, said means comprising a plurality of normally folded bars pivotally connected at their ends, shroud lines threaded loosely through said eyelets, alternate pivotal connections being connected with said neck, and the other pivotal connections being connected with said shroud lines for moving the bars into end to end relation when a pull is exerted on the shroud lines for opening the neck and holding the same in its full open position, and means 10 cooperable with said bars to restrain the same from pivotal movement in one direction beyond a predetermined degree. 15

6. A parachute comprising a pear-shaped canopy having an open neck, eyelets carried by said neck, a plurality of rigid bars, sleeves pivotally connecting the ends of the bars one with the other to provide a normally folded ring encircling said neck, pivotal connections between said neck and alternate sleeves, and operating connections between the shroud lines and the other of said sleeves so arranged as to move the bars to ring formation when a pull is exerted on the shroud lines for positively opening and holding the neck in a full open position. 30

7. A parachute comprising a pear-shaped canopy having an open neck, eyelets carried by said neck, a plurality of rigid bars, sleeves pivotally connecting the ends of the bars one with the other to provide a normally folded ring encircling said neck, pivotal connections between said neck and alternate sleeves, operating connections between the shroud lines and the other of said sleeves so arranged as to move the bars to ring formation when a pull is exerted on the shroud lines for positively opening and holding the neck in a full open position, and means 45 cooperable with said bars for restraining the latter from relative pivotal movement in one direction beyond their neck opening position. 50

8. A parachute comprising a pear-shaped canopy having an open end with the neck extending downwardly in the falling position of the parachute, a valve opening in the upper end of the canopy, a loop-shaped bracket attached to the canopy and extending upwardly from its top, a valve for closing said valve opening, a stem connected with said valve and slidably extending through an opening in said bracket, resilient means cooperable with said bracket and said stem for yieldingly holding the valve in a closed position, and a pull line connected with said valve for opening the same against the tension of said resilient means. 55
